UNITED STATES PATENT OFFICE.

WILLIAM R. KINNEAR, OF NEW YORK, N. Y.

SHEET-METAL RADIATOR.

SPECIFICATION forming part of Letters Patent No. 787,845, dated April 18, 1905.

Application filed December 21, 1903. Serial No. 186,033.

To all whom it may concern.

Be it known that I, WILLIAM R. KINNEAR, a citizen of the United States, and a resident of the borough of Manhattan, in the city and State of New York, have invented certain new and useful Improvements in Sheet-Metal Radiators, of which the following is a specification.

My invention relates more especially to sheet-metal radiators of that type in which a central air-flue is surrounded by a chamber for the circulating or heat-conveying medium; and it consists in certain novel features of construction to be hereinafter fully described, and particularly pointed out in the claims, reference being had to the accompanying drawings, in which—

Figure 1 is a vertical longitudinal section through a radiator composed of a plurality of units constructed in accordance with my present invention. Fig. 1^a is a detail view of a modified construction of a part shown in Fig. 1. Fig. 2 is a horizontal section through one unit. Fig. 3 is an elevation of a part of one unit on an enlarged scale, and Fig. 4 is a detail view of the blank thimble for closing openings in the radiator.

1 represents the air-flue, and 2 the chambers for the circulating medium in each unit of the radiator.

30 The chambers 2 are connected by struck-up bosses 3, united by a seam, and the adjacent units of the radiator are connected by similar seamed bosses 4, all of which bosses are preferably constructed with inwardly-projecting radial flanges, which are united to form the seams.

In steam-radiators it is desirable to have no connection between the upper ends of adjacent units. One feature of my invention therefore consists in providing a closure for the openings which occur in the construction above described, such closure consisting of a thimble 5, having cylindrical walls and a closed end fitting within the opening to be closed and expanded on opposite sides thereof, its open end forced firmly against the flange of the opening. This closure also serves to close the upper end openings of the radiator, and in order to provide a neat finish for such end

50 closures the thimble has soldered within it a nut 6 and is covered by a cap 7, held in place by a screw 8, passing through the cap and entering the nut.

Sheet-metal radiators have a tendency to expand under internal pressure. Hence another 55 feature of my invention consists in depressing the flat sides of the units to form stiffening-panels 9 and in further depressing the lowest portion of said panels to form bosses 10, which abut against the inner walls of the 60 unit, said bosses and inner walls being tied together by open thimbles 12, as shown in Figs. 1 and 2, the metal of the boss being expanded into locking relations with the inner wall in the former case, but this additional 65 lock being omitted in the latter case.

Double tubular radiator units have heretofore been formed by inner and outer complete tubes. It is advantageous, however, under some circumstances to divide these tubes 70 into two parts each and instead of uniting them into tubes to connect the respective halves on each side, so as to form two identical unit members each provided with its own chamber 2 and forming between them the air-flue 1 when they are brought together. Such 75 construction is shown in Fig. 2.

The inner and outer walls are preferably united along their vertical edges by outwardly-projecting seams 13, and the two 80 members are held together by a dovetail binding-strip 14, also by the circulating-passages 3, already described, which connect the circulating-chamber in one member with that of the other and extend across the air-flue. 85

The several features above described coöperate to form a radiator unit of superior construction.

Having thus described my invention, what I claim is—

1. A sheet-metal radiator comprising a plurality of units constructed of sheet metal, open bosses extending from the outer walls of the units and connecting adjacent units; inwardly-projecting radial flanges in the openings between the units, thimbles closing the 95 passages between the units, having an open side, the metal of said thimbles extending on

opposite sides of the inwardly - projecting flanges and covering-caps provided on the open sides of the thimbles in the end bosses.

2. A sheet-metal radiator unit constructed of two symmetrical halves abutting along their vertical edges and having their abutting sides concave between said vertical edges and separated at top and bottom so as to form a vertical air-flue through the unit; each of said halves being constructed of two sheets of metal united completely around their edges but spaced apart between their edges to form a chamber for the reception of a heating medium.
- 15 3. In combination with a radiator having an opening therein, a closure for said opening comprising a thimble having a closed end, inserted in said opening and expanded on opposite sides of the opening to hold it in place
- 20 therein and a cap covering the open end of said thimble, a nut secured to the inner face of the closed end of the thimble, and a bolt securing the cap to said nut.
4. In a sheet-metal radiator unit, a wall de-
- 25 pressed inwardly to form a stiffening-panel, an opposed wall, a portion of the depressed panel being pressed still further inwardly into abutment with the opposed wall, and suitable connections between the opposed
- 30 wall and the abutting portion of the depressed panel to prevent expanding of the walls under internal pressure.
5. A sheet-metal radiator unit having one of two opposed walls depressed to form a lon-
- 35 gitudinal stiffening-panel, with a space between said panel and the other opposed wall, and having a boss depressed from said panel into abutment with said other opposed wall, and a thimble passing through the parts and
- 40 uniting them.
6. A sheet-metal radiator unit constructed of inner and outer tubes with a central air-space; the outer tubes being depressed to form stiffening-panels, and having portions of said
- 45 panels depressed to form bosses abutting against the inner tubes of the unit, and thimbles passing through the bosses and inner tubes and tying said parts together.
7. A sheet-metal radiator unit constructed
- 50 of two symmetrical halves united along their vertical edges, spaced apart between said edges and separated at top and bottom so as to form a vertical air-flue through the unit; each of said halves being constructed of two sheets of
- 55 metal united completely around their edges, but spaced apart between their edges to form a chamber for the reception of the heating medium.
8. A sheet-metal radiator unit constructed
- 60 of two symmetrical halves united along their vertical edges, spaced apart between said edges and separated at top and bottom so as to form

a vertical air-flue through the unit; each of said halves being constructed of two sheets of metal united completely around their edges, 65 but spaced apart between their edges to form a chamber for the reception of the heating medium, the inner walls of the respective halves being connected by struck-up open bosses to form a circulating-passage between the halves. 70

9. A sheet-metal radiator comprising a plurality of units each constructed of two symmetrical halves united along their vertical edges, spaced apart between said edges and separated at top and bottom so as to form a 75 vertical air-flue through the unit; each of said halves being constructed of two sheets of metal united completely around their edges, but spaced apart between their edges to form a chamber for the reception of the heating me- 80 dium, the inner walls of the respective halves being connected by struck-up open bosses to form a circulating-passage between the halves and the outer walls of said halves being also provided with struck-up open bosses, and the 85 opposed outer bosses thus formed being suitably united to connect the units of the radiator together.

10. A sheet-metal radiator formed of two members each comprising inner and outer 90 walls with a chamber between them and united by seams along their edges to close said chamber; said members being connected along their vertical edges, by clamping-strips engaging the seams thereof, to form an air-flue between 95 the members.

11. A sheet-metal radiator unit comprising two members each formed of inner and outer walls united along their edges to form a chamber for the circulating medium and having the 100 vertical edges of the members connected to form an air-flue between the members; the opposed inner walls of said members being connected at upper and lower points by circulating-passages between the chambers; and the 105 inner and outer walls of each member being brought into abutment and suitably tied together at points between said upper and lower circulating-passages.

12. A sheet-metal radiator comprising two 110 chambers each formed by an inner wall and an outer wall suitably connected along their vertical edges by outwardly - projecting seams, and binding - strips having flanges engaging behind the adjacent seams of the respective 115 members, holding the members together and closing the air-flue formed between them.

The foregoing specification signed this 15th day of December, 1903.

WILLIAM R. KINNEAR.
